United States Patent [19]

Shalon et al.

[11] Patent Number: Des. 285,290

[45] Date of Patent: ** Aug. 26, 1986

[54] MODULAR PREPARATIVE HIGH
PRESSURE LIQUID CHROMATOGRAPHY
COLUMN

[75] Inventors: Yehuda Shalon; Tadmor Shalon;
Danny D. Meyer, all of St. Louis
County, Mo.

[73] Assignee: Hp Chemicals, Inc., St. Louis, Mo.

[**] Term: 14 Years

[21] Appl. No.: 492,802

[22] Filed: May 9, 1983

[52] U.S. Cl. D10/81; D24/8

[58] Field of Search D24/8; D10/81; 210/656,
210/657; 422/89, 93

[57] CLAIM

The ornamental design for a modular preparative high pressure liquid chromatography column, as shown and described.

DESCRIPTION

FIG. 1 is an isometric view of a modular preparative high pressure liquid chromatography column, showing my new design;

FIG. 2 is a side elevational view, the opposite side being a mirror image thereof;

FIG. 3 is an end elevational view, the opposite end being a mirror image thereof.
